CLAYTON A. DUNHAM, OF GLENCOE, ILLINOIS, ASSIGNOR TO C. A. DUNHAM COMPANY,
OF MARSHALLTOWN, IOWA, A CORPORATION OF IOWA

DIFFERENTIAL HEATING SYSTEM

Application filed April 4, 1924, Serial No. 704,142. Renewed November 9, 1927.

My invention relates to a steam heating system comprising separate supply and return mains and which is provided with mechanism for creating a low pressure in the return main; and the primary objects of the invention are: To provide a new and improved heating system in which the steam is circulated through the radiators, under ordinary conditions, at pressures much below atmospheric pressure; to provide a new and improved exhausting mechanism which will tend to create and maintain a relatively constant but regulatable pressure differential as between the supply and return mains; to construct and arrange this mechanism so that it withdraws from the return pipe air and non-condensable gases only, and to provide for the return of the condensate to the boiler of the steam generator by gravity, or by means of a return trap or other device independent of the exhausting mechanism; to construct the system so that the boiler and radiators may be maintained at pressures approximating the low pressure of the return main so as to increase the volume of steam generated and its equal distribution to the radiators when the fire is low and to hasten the delivery of steam to the radiators when the apparatus is first started up; to provide means whereby this last mentioned effect may be obtained without drawing any appreciable amount of steam from the radiators into the return main; to provide means whereby the rate of generator of steam, that is, the fire of the generator may be controlled, so as to maintain the supply main, radiators and boiler at low pressures approximating that maintained in the return main or at any higher pressure as may be desired; to construct the apparatus so that if the boiler pressure exceeds that at which condensate will return to the boiler by gravity a counterbalancing pressure will be built up in the return main which will permit such gravity return of condensate; and to construct the apparatus so that in case the exhaust mechanism fails to work the system will, nevertheless, be operated in the same manner as the ordinary gravity system using pressures above atmosphere.

The invention contemplates, more specifically, an electrically driven water pump and a jet exhauster arranged in a hurling circuit with the pump for creating the low pressure in the return main, and, assuming the use of this form of exhausting mechanism, the invention has for further objects: To provide an exhausting mechanism which will be small, compact and which will produce a relatively high vacuum with small consumption of current; to provide for supplying water to the hurling circuit from a source independent of the return main from the radiators, preferably, from the drip pipe or continuation of the supply main, which pipe is connected with the boiler, whereby condensate from the drip pipe and boiler water will be utilized for the hurling circuit and any excess of condensate returned by gravity to the boiler; to provide for the connection of the pump on its induction side to the drip pipe and on its eduction side to the atmosphere so that the force of the jet developed by the pump will be augmented by steam pressure in the boiler; to arrange the pump below the boiler water line to insure a constant supply of water to the hurling circuit; to arrange the exhausting pipe between the vacuum space of the jet exhauster and the return main so that air and non-condensable gases only will be drawn into the hurling circuit; to arrange the hurling circuit so that the water therein is used over and over again, fresh water being introduced only to replenish losses so that, because of the relatively low temperature of the hurling water the efficiency of the jet exhauster will be at a maximum; to provide the return main with a vertical leg extending above the boiler water line to such a distance that water collecting therein overbalances any boiler pressure not in excess of that contemplated by the normal operation of the system; and to provide the exhausting mechanism and the other parts of the apparatus with certain check valves and float controlled valves whereby the system may be operated at or above atmospheric pressure if circumstances require.

The invention consists of the new and im-

proved constructions, arrangements and devices to be hereinafter described and claimed for carrying out the above stated objects and such other incidental objects as will be mentioned in the following description of the preferred embodiments of the invention shown in the accompanying drawings.

It will be understood, however, that while the invention contemplates the use of all the devices shown in combination, and their combined use gives rise to the advantages to be hereinafter set forth, the invention is not to be considered as limited to the joint use of all of the novel features shown and described.

The invention is illustrated in certain preferred embodiments, in the accompanying drawings, wherein

Fig. 1 is a fragmentary view, in elevation, of one form of the invention.

Fig. 2 is a sectional view of the inlet valve on one of the radiators of the system.

Fig. 3 is a sectional plan view illustrating a portion of the pumping mechanism for maintaining pressure differential between the supply and return mains, this figure being taken on line 3—3 of Fig. 5.

Fig. 4 is a sectional elevation of the pumping mechanism.

Fig. 5 is a sectional view on line 5—5 of Fig. 4.

Fig. 6 is a sectional view of the jet exhauster forming part of the pumping mechanism.

Fig. 7 is a vertical sectional elevation of the device, hereinafter referred to as the "air eliminator", for discharging air or other non-condensable gases from the return main.

Fig. 8 is a vertical sectional view of the differential pressure actuated device for controlling the pump motor.

Fig. 9 is a vertical sectional view of a modified form of radiator inlet valve.

Fig. 10 is a fragmentary elevation, partly diagrammatic, of the heating system of my invention modified to provide a return trap for introducing condensation from the return main into the boiler.

Referring first to Figs. 1 to 8 inclusive: A and A' designate two of the radiators of the heating system, and B is the steam supply main opening out of the steam space of steam generator C and connected by supply pipes D with radiators A and A', respectively. E

55 (Fig. 2) is a manually controlled valve between supply pipe D and each radiator, and F is a steam trap of any preferred construction at the outlet of the radiator, this trap being connected by a pipe 1 with the return main G, which latter is connected with the boiler of generator C below the water level therein and is provided with a check valve 2 opening toward the boiler. At D' and 1' are indicated supply and return pipes leading to another radiator, or group of radiators, on

another floor of the building. H is a drip pipe connecting the end of the steam main B with return main G between the check valve 2 and the boiler. I is a thermostatic trap arranged in a pipe 3 between the drip pipe H and the return main G for venting air from the drip pipe into the return main. J (Fig. 7) is an air eliminator connected by pipes 4 and 5 with the return main G and provided with an outwardly opening check valve 6. K is a thermostat, preferably, but not necessarily, employed for controlling the dampers 7 and 8 of the steam generator through the instrumentality of a damper operating motor 9, of common construction.

Condensation is returned to the boiler from return main G and drip pipe H by gravity. The air and non-condensable gases are withdrawn from the return main G through a pipe 10 by means of an exhausting apparatus 85 consisting preferably of the following instrumentalities: L is a hurling water tank connected by pipe 11 to the drip pipe H. M is a centrifugal pump receiving water from tank L and forcing the same through a jet 90 exhauster N to the suction space of which is connected the pipe 10, above referred to, leading from the return main G; this pipe being provided with a check valve 12 opening toward the jet exhauster. Water from 95 the jet exhauster passes into an air separating tank O and thence back to the hurling water tank L, the air and gases being discharged to the atmosphere (under certain conditions) through an orifice 13 which is 100 closed by a valve 14 operated by a float 15, the same float operating a valve 16 controlling the port 17 between the air separator O and the hurling water tank L. The port 13 is provided with an outwardly opening check 105 valve 18.

The pump M is preferably driven by an electric motor P, the controlling switch Q of which is governed by a differential pressure device R, the low pressure chamber of which 110 is connected by pipe 19 with pipe 10 leading to the return main G and the high pressure side by means of pipe 20 with the hurling water circuit which is substantially at boiler pressure. S is a differential gauge or pressure indicator connected by pipe 21 to pipe 10 (low pressure side of the apparatus) and by pipe 22 to pipe 11 (high pressure side of the apparatus).

From the above it will be observed that the 120 induction side of the pump M is under boiler pressure; that the exhauster removes air (which term is intended to include non-condensable gases) from the return main of the heating system, drawing the same into the 125 hurling water circuit to be discharged to the atmosphere by the air separator, without drawing into the hurling water circuit any water of condensation from the return main. The horizontal leg 23 of the return main is 130

considerably above the water line of the boiler, designated *a, a*, so that water of condensation from the heating system will flow into the boiler of the generator by gravity of the hydrostatic head of water collecting in the vertical portion 24 of the return main above the boiler water level so long, that is, as the boiler pressure is effectively less than the force exerted by such water column; that the return main is shut off from boiler pressure by check valve 2; that accumulation of water in the drip pipe to a height balancing boiler pressure will result in introduction of excess water in this pipe into the boiler; and finally, with the radiators filled with steam thermostatic valves F will be closed, opening only to void the radiators of air and water so that the exhausting apparatus cannot draw steam, in any substantial quantities, into the return main, while with insufficient steam supply to fill the radiators the thermostatic valves F will be open so that the entire system will operate as a vacuum system, thereby effecting a lowering of the evaporation temperature of the boiler water.

The operation of the system under various possible conditions will be summarized hereafter. Before doing this I will described in greater detail the constructions of the several instrumentalities generally referred to above.

Radiator valve E (Fig. 2). 25 is a casing having an inlet port 26 communicating with supply pipe D and adapted to be closed by a valve 27 arranged on a structure 28 having a stem 29 provided on opposite sides with notches 30 for non-rotatable engagement with the nut 31 which has threaded engagement with an internally threaded sleeve 32 adapted to be rotated by a handle 33, the sleeve and handle being supported on the bonnet 34 of the valve casing. The stem 29 is non-circular in cross section and extends through an opening of similar shape in a guide plate 35 which is interposed between the upper edge of the casing and the bonnet.

Consequently, when the handle 33 is turned nut 31 is forced downwardly so as to seat the valve 27 over port 26. The outlet port of the valve casing is through a boss 36 secured by union 37 to a nipple 38 which is screwed into radiator A. A plate or disc 39 formed with an orifice 40 is arranged in the boss 36 and is held against a shoulder 41 by a split ring 42. The orifice plate 39 is removable so that the valve for each of the radiators of the heating system may be fitted with a plate having an orifice of the proper size to provide for the admission to the radiator of the proper amount of steam. The orifices are of a size, when the system is filled with steam, to admit enough steam to make up for condensation. That is the pressure in the radiators will equal the supply pipe pressure. The orifice plates function to dam

back the steam only when the system is started up. Thereby they insure the full supply of steam to the radiators remote from the generator.

In place of the radiator valve E with its orifice plate 39, a pressure reducing radiator valve may be used, such as is shown in Fig. 9, which may be connected to the radiator by same means as is shown in Fig. 2 for connecting the valve E; namely, a nipple 38 screwed into the radiator and a union 37 connecting a boss 43 on the casing of the pressure reducing valve with nipple 38. The casing of the pressure reducing valve consists of upper and lower casing members 44, 45. Between these members is a flexible diaphragm 46. The lower casing member has an inlet port 47 in which is arranged a valve seat 48. A valve body 49 cooperates with seat 48 and is provided with a stem 50 secured to a button 51 to which diaphragm 46 is fastened. A flexible, corrugated structure 52 is secured at the top between the stem members 53, 54 and at the bottom against a web 55 of the upper casing member by means of a nut 56. Stem member 53 is threaded for nut 57 and has a disc-like projection 58 adapted to bear, adjustably, upon a spring 59 which seats upon web 55 above referred to. Steam from the radiator supply pipe D can by-pass the valve seat 48 through a duct 60 so as to reach the under side of diaphragm 46. The chamber 61 above the diaphragm is connected to the interior of the radiator by a pipe 62. Stem member 53 projects into a bonnet 63 on the upper casing member 44. This bonnet is internally threaded to receive the threaded portion 64 at the end of an operating stem 65 which is provided with a hand grip 66 which can be utilized, however, only for closing the valve. The valve body 49 may be seated on the valve seat 48 by turning the hand grip 66 but when the valve is not seated in this positive way its position with respect to the valve seat will depend upon the difference of steam pressures on opposite sides of diaphragm 46 and upon the pressure of spring 59 which may be varied by adjustment of nut 57.

When the pressure builds up in the radiator to a certain point diaphragm 46 will be deflected downwardly so as to close or throttle the steam inlet to the radiator. When the pressure falls in the radiator the diaphragm will be raised so as to increase the effective size of the inlet port. When this device is used radiator pressure may be less than supply pipe pressure, but will be dependent thereon.

The thermostatic trap F may be of any preferred construction provided it is capable of functioning effectively over the range of pressures which the system handles. It functions when steam is in contact with it to close the outlet of the radiator, opening, however, at the temperature of water to keep

the radiator free from water and allowing the outflow of air when the system is started up.

The trap I may be of similar construction 5 and is arranged so that air may be vented from the drip pipe H through return main G, the trap preventing the flow of steam from one of these pipes to the other. As traps of this sort are in common use, detailed description 10 of the same will not be required.

Air eliminator J (Fig. 7). 67 is a casing connected to pipes 4 and 5 above referred to and containing a float 68. On the upper end of float 68 is a valve 69 which extends through 15 a perforated baffle plate 70 secured between the upper flange 71 of casing 67 and a cover plate 72. Preferably a downwardly curved baffle plate 73 is secured to the plate 70. Valve 69 is adapted to seat, when the float is 20 raised, on a valve seat 73^a. 74 is an air exit pipe provided with the outwardly opening check valve 6 referred to above. The float 68 is provided at the bottom with a guide pin 25 75 extending into an orifice in a bridge 76 across the outlet opening 77 of casing 67.

Exhausting apparatus. The hurling water chamber L and the casing of the air separator O are preferably formed of a single casting as shown in Fig. 4. Water enters chamber 30 L from the drip pipe H through pipe 11 and leaves the chamber L through a port 78 (Fig. 3). The casing of centrifugal pump M consists of a web 79 depending from tank L and a plate or casing member 80 secured to the web 35 and to the front wall 81 of the tank by screws 82. Plate 80 is formed so as to provide a duct 83 extending from port 78 to the center of plate 80 in line with the shaft 84 of the pump. The latter is coupled at 85 to the armature shaft 86 of motor P and is supported 40 in a bearing 87 carried by a bracket 88 on the under side of tank L and by a bearing 90 in a boss 91 on the rear face of web 79. The impeller of the pump is keyed to shaft 84 at 45 92 and consists of a pair of discs 93, 94 connected by curved blades 95. Disc 94 is formed with an opening 96. The discharge space 97 of the pump casing communicates with an outlet duct 98.

50 From duct 98 the water is forced through the jet exhauster shown in Fig. 6. This device consists of a casing 99 formed with a vacuum space 100 connected with the return main G by means of pipe 10; the casing being 55 secured by nipple 101 and union 101^a to the end of duct 98 and being formed with a bore 102 tapered from top to bottom. A discharge nozzle 103 is fitted into an enlargement 104 of bore 102 and extends across the vacuum 60 space 100 into proximity with the end of a receiving nozzle 105 screwed into the top of casing 99 and formed with a straight bore 106, and beyond this, with a flared bore 107, the upper end of member 105 being connected 65 with a conduit 108 which extends to an open-

ing 109 in the side of the air separator O. The purpose of tapering bore 102 is to nullify the effect of the possible warmth of the water in the hurling circuit by utilizing the expansion of the stream in bore 102 to increase the 70 kinetic energy of the jet from nozzle 103.

The float 15 is carried on a lever 110 pivoted to a clevis 111 and provided with a depending arm 112 to which is pivoted valve 16, the latter being arranged to cooperate with a 75 valve seat 113 fixed in the front wall 114 of the air separator. Valve 14 is arranged on the end of a rod 115 pivoted to lever 110 and cooperates with a seat formed on an air venting member 116, the bore of which has been 80 designated 13. Check valve 18 is pivoted in a vent member 117 on the outside of the front wall 114 of the air separator. The bearing 90 of the pump shaft 84 is preferably lubricated by water taken from the discharge space 85 97 of the pump casing through a pipe 118.

The operation of the pump is intermittent, the pump being designed to maintain a determinate, but variable, pressure differential as 90 between the boiler and supply pipe side of the heating system and the return main from the radiators.

Q is a circuit breaker, of any desired type, operated by the pressure actuated device R shown in Figs. 4 and 8. This device consists 95 of an upper casing member 119, a lower casing member 120, a flexible diaphragm 121, the edge of which is clamped between the flanges of said casing members, a rod 122 secured to the diaphragm, and a coiled spring 123 interposed between the upper casing member and the diaphragm. Rod 122 extends through a stuffing box 124 and is pivoted to a lever 125 fulcrumed at 126 to the bracket 126^a which supports the switch Q. A link 127 connects lever 125 with the operating arm 128 of switch Q. The chamber 129 below the diaphragm 121 is connected by pipe 20 to some point in the system under boiler pressure. For example, it may be tapped into the side of duct 98. The chamber 130 above the diaphragm is connected to the low pressure side of the system, for example, by pipe 19 extending to pipe 10. The differential controller is shown with its diaphragm 110 in the position it will occupy when the pump is operating. If the pressure in the return main is diminished, relative to boiler pressure, through operation of the exhausting mechanism, or if the boiler pressure increases, relative to the pressure in the return main 115 so that the determinate difference in pressure exists for which the controller is set to act, the diaphragm will be raised raising rod 122 and throwing switch arm 128 to break the circuit through the pump motor P. For 120 the purpose of adjusting the differential controller, link 127 is made in two parts which are slotted and secured together by set screws 125 131.

Summary of operation.—(Figs. 1 to 9 inclusive.) Any one of several different operating conditions may prevail in the system as follows:

5 *First. Operation in starting.*—The thermostatic traps F of the radiators will be open. Assuming that the current is available to supply the pump motor, the pump will be started since there will be substantially no difference in pressure between the boiler and the return main G. The circulation of the water through the hurling circuit will produce a pressure below atmosphere in the vacuum chamber 100 of the jet 70
10 exhauster and throughout the entire system since the radiators, supply main B and the steam space of the boiler will be in communication with the return main through the open 75
15 thermostatic traps F. As a result the evaporation of the water will be commenced at 80
20 a lower temperature than if the boiler were under atmospheric pressure. That is to say, the apparatus will start to supply steam to the radiators, though at a lower temperature, than if the boiler were subject to atmospheric pressure. Moreover, the steam 85
25 delivered by the boiler will be evenly distributed throughout all of the radiators of the heating system. The exhausting apparatus 90
30 effects the withdrawal of air and water of condensation from the radiators but the air and entrained moisture only are drawn into the hurling circuit. The water of condensation collects in the vertical leg 24 of the 95
35 return main G and when the column of water in pipe 24 stands above the level a, a of the water in the boiler to an extent sufficient to 100
40 overbalance the boiler pressure, the condensate will enter the boiler by gravity. Any 105
45 excess of condensation in the drip pipe will return to the boiler by gravity and since the drip pipe is under boiler pressure the water in pipe H will stand at the level of the water in the boiler, that is, a height just a trifle 110
50 above pipe 11 and at about the level of the upper portion of the hurling circuit L so that the pump will always be primed. The 115
55 hurling water from the jet exhauster, mixed with the air drawn from the return main, is discharged into the air separator O. The air escapes to the atmosphere through vent port 13. The water is trapped in the separator chamber by valve 16 until a sufficient amount accumulates to raise float 15, whereupon valve 14 is moved to close the air vent and valve 16 unseated. As soon as the accumulation of air pressure in the separator O plus the static head of water therein overbalances boiler pressure in tank L the water 120
60 from the air separator passes through duct 17 into the hurling water tank L. The hurling water circuit is, however, continuously supplied with water from the drip pipe through pipe 11 so that no interruption or 125
65 impairment of the exhausting jet results

through the interruption of the discharge of water from tank O to tank L. A sufficient supply of water to the pump through pipe 11 is insured since the drip pipe H is under boiler pressure and by the fact that pipe 11 is slightly below the water level of the boiler. The function of pipe 3 with its steam trap I is, first, to vent any air in the drip pipe to the return main so that there will be no chance of the pump becoming air bound; and, second, to insure quick passage of steam through the steam supply pipe to the radiators remote from the boiler and the rapid elimination of condensate from said steam supply pipe. So long as the radiator traps F remain open the pump will continue to operate as the difference in pressure between the return main and the supply main will be less than that at which the differential controller R is set to function. 130

temperatures the radiating system will be at pressures below atmosphere. The radiating system will be at atmospheric pressure or above only in very severe weather. By means of orifice plates 39 (Fig. 2), the orifices of which are proportioned in accordance with the size and position of the radiators in the system, or by means of the pressure reducing valves of Fig. 9, the distribution of steam to the several radiators will be uniform. This may, of course, be varied by manual adjustment of the radiator valves. If the pressure in the supply main increases, relatively to the lower pressure in the return main, or if the pressure in the return main decreases, due, for example, to diminished condensation, and this pressure differential reaches the point at which the controller R is set to act, the pump will be stopped until, through leakage of air into or accumulation of condensate in the return main, or reduction in the rate of steam supply, the pressure differential is reduced to a point which sets the pump again in operation. The action of the pump is, therefore, intermittent. It maintains, effectively, a constant difference in pressure between the supply and return sides of the system. Condensate in the return main can at all times, under the conditions assumed, flow back to the boiler by gravity since the pressure in the boiler will not be in excess of the static head of water in pipe 24.

The temperature of the steam in the radiators depends upon the amount of steam per unit of time admitted to the radiators. This, in the present embodiment of the invention, is adjusted by controlling the generation of steam through thermostatic control of the dampers of the generator.

When the system is operating so that the pump tends to produce subatmospheric pressures in the return main and throughout the system, check valves 6 of air trap and eliminator J and 18 of air separator O will be closed to permit the maintenance of the low pressure.

At any time in the operation of the apparatus when the boiler pressure is greater than will be balanced by a column of water equal in height to the distance between pipe 11 and the top of air separator O, the separating chamber will be filled with water reaching the chamber through the pump and jet exhauster. In such case the water is prevented from entering the return main by check valve 12. The water in the separating chamber will be prevented from flowing to the atmosphere because of the closing of air outlet duct 13 under action of float 15. Now, if the pump starts as a result of diminished pressure differential, the jet exhauster will draw air from the return main into the air separator so as to create an air pressure above the water in the separator. This body

of compressed air will lower the water level in the air separator, causing the water to flow into the hurling water tank L, and if this is filled, to back out through pipe 11 into drip pipe H. As soon as the air pressure in the air separator has lowered the water level sufficiently to allow valve 14 to unseat through subsidence of the float, the accumulated air in the air separator will escape through outlet 13 to the atmosphere.

The normal operation of the system contemplates the maintenance of a pressure differential as between the supply pipe and the return main G (whether the system is at sub-atmospheric pressures or at pressures slightly above atmosphere) which is slightly less than the pressure exerted by the hydrostatic head of a water column equal in height to the distance between the water level of the boiler and the horizontal leg 23 of the return main. To avoid circumlocution this differential will be referred to as the normal differential as between the supply pipe and return main. Where the system is provided with a thermostat K for controlling the dampers of the steam generator, this thermostat may be set so that steam will be generated at a rate just rapid enough to equal the heat lost from the building. For average temperatures the steam generated will be insufficient to fill the radiators at atmospheric pressure and therefore expands so that the pressure in the radiators is less than atmosphere. The pressure differential may be no more than necessary to move the medium through the radiating system. However, the system is intended to operate, when circumstances require it, with a pressure difference above the normal differential, as mentioned above; and this phase of the operation of the system will now be described.

Third. Operation with pressure difference above normal.—Whenever the pressure difference is above normal, as just defined, as will be the case when the rate of heat loss is abnormally high, the pump will be out of operation since differential controller R will have functioned to break the circuit through the pump motor. The pump will remain out of operation until the pressure difference has been reduced to a point below normal. Under these conditions water will accumulate in the vertical leg 24 of the return main filling the same up to the top and also filling the air trap and eliminator J, the float 68 of which is caused to rise so as to seat valve 69 to close the vent pipe 74 (Fig. 7). The continued flow of water of condensation and gaseous fluids from the radiators, by gravity and the pressure difference between the supply and return sides of the system, will create a pressure in pipe 23 of the return main and in the air trap and eliminator J above the water line therein, until the pres-

sure in the return main plus the pressure of the water column in pipe 24 overbalances boiler pressure whereupon water from the return main will flow into the boiler by gravity. If the pressure difference is reduced to the point where the differential controller R acts, the pump will be started.

Fourth. Operation with declining fire and the pump operative.—In case the fire declines so as to supply insufficient steam to fill the radiators, the system will function substantially as when the apparatus is first started up, that is, as has been described in paragraph first. The exhausting apparatus will be in operation since the pressure differential is below normal. But with insufficient steam in the radiators thermostatic traps F will open so that the reduced pressure created by the exhausting apparatus will extend to the radiating system and the steam space of the boiler. This will diminish the evaporation temperature of the boiler water, increasing the amount of evaporation so as to increase the supply of steam to the radiators. Thus the radiators will be automatically filled with steam but at a lower temperature.

Fifth. Operation with the pump out of action and the boiler at or below a pressure corresponding to the static head of the return main.—It is one of the advantages of my invention that the system will operate even if the pump through failure of current to the motor, for example, should cease to act. Under these circumstances, and with the boiler pressure less than the hydrostatic head of a water column of a height equal to the distance between the water level in the boiler and the horizontal leg 23 of return main G, water of condensation in the return main will flow by gravity into the boiler. With the apparatus operating in this manner one does not have the advantages resulting from the maintenance of a constant pressure differential as between supply piping and return main and the economies which follow from operation at sub-atmospheric pressures during average weather conditions but the system will, nevertheless, operate successfully. This is because the return of condensate from the radiators to the boiler is brought about by gravity and is independent of the functioning of the pump.

Sixth. Operation with the pump out of action and the boiler at a pressure greater than that corresponding to the static head of the return main.—Under these conditions the accumulation of condensate in the return main will flood the air trap and eliminator J causing its float to close the vent pipe 74. The continued flow of condensate from the radiators compresses the air in the return main above the water so that a pressure is obtainable approximating boiler pressure to a greater or less extent. This partial balancing of return main pressure against boiler

pressure permits the static head of water in the return main to force condensate into the boiler.

Seventh. Operation with the pump inactive and a declining fire.—Under these conditions the thermostatic radiator traps F will open and a reduction of pressure will result in the system due to the condensation of steam in the radiators and supply piping, the check valves on the air eliminator J and air separator O preventing the entrance of air into the system. The degree of vacuum will not be as great, however, as it would be with the pump in operation. The air present in the system at the time the fire starts to decline and that subsequently entering by leakage will necessarily expand as the decrease in pressure proceeds and as the pump is not in operation no means is available for decreasing the amount of this air.

In Fig. 10 a system is shown operating upon the general principles above described, but modified so as to include a return trap for introducing condensate from the dry return main into the boiler. In Fig. 10 the elements of the heating system common to the modification there shown and the form of the invention illustrated in the previous figures are given the reference letters and numerals heretofore used. In the modified form of the apparatus the horizontal leg 132 of the return main G extends to a return trap T. The vertical leg 133 of the return main is connected to the bottom of trap T. The return trap is of a type in common use. Water collects in the trap, the bottom of which is in free communication with the pipe leading to the boiler. The trap has an air vent pipe 134 and a pipe 135 connecting it with the boiler. The openings between the traps and these pipes are provided with valves under control of a pivoted float 136. When the float is down vent pipe 134 is open and steam pipe 135 closed. When enough water has accumulated in the trap to raise the float, the valve controlling the air vent pipe is closed and the valve controlling the steam pipe opened so that a steam pressure is exerted on the water in the trap balancing boiler pressure and the water flows by gravity into the boiler. In the drawings I have shown a return trap which is the subject matter of the patent of Oscar G. Johnson, 1,509,299, granted September 23, 1924. Any other trap of this general type might be used in place of that shown.

In connecting up the return trap with the heating system of my present invention a check valve 137 is arranged in pipe 132, the valve opening in the direction of the trap, and the air eliminator J is connected with a T 138 on the vent pipe 134 by an equalizing pipe 139 provided with a check valve 140 which opens toward the air eliminator. Projecting from the other side of the T 138 is a pipe 141

open to the atmosphere and provided with an outwardly opening check valve 142.

Operation of the system with return trap.—(Fig. 10.) When the heating apparatus is first started up the operation will be the same as in the gravity return system of Fig. 1. That is, the thermostatic traps of the radiators will be open and the entire system will operate at sub-atmospheric pressure, with the result that steam will be delivered to the radiators more quickly than if the boiler were under atmospheric pressure and the distribution of steam will be uniform throughout the system. Condensation collecting in the return main will flow by gravity through the trap T and into the boiler under the hydrostatic pressure of the water in the pipe 133 and in the trap. The vacuum is maintained by check valves 6 and 142. The horizontal pipe 132 of the return main G is formed, preferably, with a downward bend 143 to overcome the resistance of check valve 137.

So long as the pressure differential as between the supply piping and the return main is at or less than normal, that is, represents a pressure equal to or less than the hydrostatic head of a water column of a height corresponding to the distance between boiler water level and the opening of pipe 132 into trap T, the condensation will flow into the boiler by gravity. Under these conditions the trap does not function as such but is merely part of the return conduit. The pump continues to operate until the normal differential is established and is automatically stopped by the differential regulator when the normal differential is exceeded.

If, however, due to excess of steam generated over condensation, the normal differential is exceeded, and this condition persists, the trap will function to return the water of condensation to the boiler as follows: Under this condition water will collect in the trap T since the water column in the trap will be insufficient to balance the assumed boiler pressure. This causes the float 136 of the trap to rise, closing the vent pipe 134 and opening the trap to the steam pipe 135. Steam enters the trap at boiler pressure and the water in the trap flows by gravity to the boiler. Check valve 137 shuts off the high pressure in the trap from the return main. The condensate collecting in the return main is prevented from escaping through the air vent of eliminator J by the float controlled valve of said eliminator. Check valve 140 prevents water from flowing out through pipe 139. When the trap has been discharged float 136 subsides, closing steam pipe 135 and opening vent pipe 134. The trap is vented of excess pressure through pipes 134, 141 and the outwardly opening check valve 142, the pressure in the trap being further reduced to that of the return main through equalizing pipe 139.

In this phase of the operation, that is, with

the pressure differential above normal, the system having a return trap as shown in Fig. 10 has a certain advantage over the system shown in Fig. 1, in that steam pressure from the boiler is employed for returning condensation to the boiler instead of a pressure developed by the pump. That is to say, electric current consumption is economized.

With a declining fire the system of Fig. 10 operates exactly the same as the system of Fig. 1.

With the pump out of action, through failure of current, for example, the system of Fig. 10 operates exactly the same as the system of Fig. 1, provided the boiler pressure does not exceed atmospheric pressure prevailing in the return main by an amount in excess of what has been termed the normal pressure differential. That is, with the pump out of action water of condensation will flow by gravity back to the boiler so long as the boiler pressure is such that it can be overbalanced by the head of water collecting in trap T and pipe 143.

If the boiler pressure exceeds this pressure the trap will operate to return the water of condensation intermittently to the boiler as heretofore described.

For indicating the difference in pressure existing at any time between the supply piping and the return main, I prefer to employ the differential pressure indicator shown in Figs. 11 to 14 inclusive and designated on Fig. 1 by the letter S. This device may be located in any suitable place on the apparatus. For example, it may be secured to the front head 114 of the air separator. The device comprises three dished or recessed plates 144, 145, 146 between which are arranged flexible diaphragms 147, 148. Pipe 21 connected with the low pressure side of the heating system leads to the chamber 149 between diaphragm 148 and plate 146. Pipe 22 connected with the high pressure side of the heating system leads to chamber 150 between plate 144 and diaphragm 147. Chamber 151 between diaphragm 147 and plate 145 is connected by a duct 152 and elbow pipe 153 with one leg 154 of a U-shaped gauge glass 155 supported by a bracket 156 depending from plate 146. The other leg 157 of the gauge glass is connected by an elbow 158 and a duct corresponding to duct 152 with the chamber 159 between diaphragm 148 and plate 145. The gauge glass contains a body of mercury 160 and chambers 151, 159, together with the pipe connections 153, 158, and the legs of the gauge glass above the mercury are filled with water. 161 is a gauge plate having graduations upwardly on the vacuum side and downwardly on the pressure side from a common zero line coinciding with the tops of the mercury columns in the gauge glass when said columns are balanced, that is, when the pressures in the supply

piping and return main are equal. Any difference of pressure as between the supply piping and return main will be indicated by the rise of one mercury column and the falling of the other.

While I have described my invention in certain preferred embodiments, I wish it to be understood that I contemplate all further modifications within the scope of the appended claims.

While the invention is shown and described as embodied in a heating system for a single building having its own steam generator, the novel constructions and arrangements constituting the invention might be utilized in connection with a central station system in which several buildings are heated from a single central boiler plant.

I do not claim specifically herein the form of apparatus shown in Fig. 10 as such apparatus is the subject of a divisional application, filed Dec. 31, 1927, Serial No. 243,861. Nor do I claim herein the invention common to this application and my previous application Serial No. 669,363, filed October 18, 1923, as such generic invention is claimed in the earlier filed application. By the term "heating medium" as used in the claims I intend to include the fluids circulated through the radiating system, to wit, the steam, vapor, water of condensation and entrained air or other non-condensable gases.

I claim:

1. Steam heating apparatus comprising in combination a steam generator, controlling devices for the generator, a radiating system, connections for supplying the radiating system with steam from the generator and withdrawing fluids therefrom comprising a supply conduit and a return conduit, means for maintaining selected pressures below atmosphere in said radiating system in accordance with the heat output desired and a predetermined difference of pressure between the supply and discharge conduits sufficient to move the steam through the system, and a thermostat connected with the controlling devices of the steam generator for limiting the quantity of steam generated to that required for supplying the radiating system.

2. Steam heating apparatus comprising in combination a steam generator, controlling devices for the generator, a radiating system having an inlet and an outlet, connections for supplying the radiating system with steam from the generator, means for maintaining selected pressures below atmosphere in said radiating system in accordance with the heat output desired and a predetermined difference of pressure between its inlet and outlet sufficient to keep up movement of the steam through the system, and a thermostat subject to heat from the radiating system and connected with the controlling de-

vices of the steam generator for limiting the generation of steam to that required for maintaining the temperature for which the thermostat is set.

3. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe connected with the generator, branch pipes leading from the outlets of the radiators to the return pipe, steam traps in said last named branch pipes, and means for maintaining selected pressures below atmospheric in said radiating system, comprising an exhausting mechanism withdrawing only non-condensable gases from the return pipe to maintain a predetermined difference of pressure between the supply and return pipes sufficient to move the steam through the radiating system.

4. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe connected with the generator, branch pipes leading from the outlets of the radiators to the return pipe, steam traps in said last named branch pipes, means for venting non-condensable gases only from the drip pipe into the return pipe and means for maintaining selected pressures below atmospheric in said radiating system, comprising an exhausting mechanism withdrawing non-condensable gases only from the return pipe to maintain a predetermined difference of pressure between the supply and return pipes sufficient to move the steam through the radiating system.

5. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe connected with the generator, extending above the water level therein to provide a hydrostatic head for return of water against the pressure in the generator, branch pipes leading from the outlets of the radiators to the return pipe, steam traps in said last named branch pipes, and means for maintaining selected pressures below atmosphere in said radiators in accordance with the heat output desired and a predetermined difference of pressure between the supply and return pipes.

sufficient to move the steam through the radiating system, this means including exhausting apparatus connected with the return pipe so as to remove therefrom only air and gases.

- 5 6. In steam heating apparatus the combination of a steam generator, a radiating system comprising a plurality of radiators, a supply pipe leading from the generator and a drip pipe leading from the supply pipe back 70
10 to the generator, branch pipes connecting the supply pipe with the inlets of said radiators respectively, a return pipe connected with the generator, branch pipes leading from the outlets of the radiators to the return pipe, 75
15 steam traps in said last named branch pipes, and means comprising exhausting mechanism connected with the return pipe so as to remove therefrom only non-condensable gases, said means maintaining selected pressures below 80
20 atmosphere in said radiators in accordance with the heat output desired and a predetermined difference of pressure between the supply and return pipes sufficient to move the steam through the radiating system, an ex- 85
25 haust pipe between the drip pipe and the return pipe and a steam trap in said last named pipe.

7. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators 90
20 respectively, a return pipe connected with the generator, branch pipes leading from the outlets of the radiators to the return pipe, steam traps in said last named branch pipes, and means comprising exhausting mechanism 95
25 connected with the return pipe so as to remove therefrom only non-condensable gases, said means maintaining selected pressures below atmosphere in said radiators in accordance with the heat output desired and a predetermined difference of 100
30 pressure between the supply and return pipes sufficient to move the steam through the radiating system, and a check valve in the return pipe which opens toward the generator.
35 8. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators 105
40 respectively, a return pipe connected with the generator, branch pipes leading from the outlets of the radiators to the return pipe, steam traps in said last named branch pipes, exhausting means connected with the return pipe so as to remove 110
45 therefrom only non-condensable gases for maintaining a predetermined difference of pressure between the supply and return pipes sufficient to move the steam through the radiating system, and means cooperating with said exhausting means for controlling the amount of steam admitted into the radiating system so as to vary the temperature of 115
50 the steam in the radiators in accordance with the heat output desired.

9. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators 120
55 respectively, a return pipe connected with the generator, branch pipes leading from the outlets of the radiators to the return pipe, steam traps in said last named branch pipes, and means comprising exhausting mechanism 125
60 connected with the return pipe so as to remove therefrom only non-condensable gases, said means maintaining selected pressures below atmosphere in said radiators in accordance with the heat output desired.

therefrom only non-condensable gases, said means maintaining selected pressures below atmosphere in said radiators in accordance with the heat output desired and a predetermined difference of pressure between the supply and return pipes sufficient to move the steam through the radiating system, said exhausting mechanism comprising a hurling water pump under the pressure in the generator on its induction side only. 75

10. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe connected with the generator, extending above the water level therein to provide a hydrostatic head for return of water against the pressure in the generator, branch pipes leading from the radiators to the return pipe, steam traps in said last named branch pipes, and means comprising an exhausting mechanism connected with the return pipe so as to remove therefrom only non-condensable gases, said means maintaining selected pressures below atmosphere in said radiators in accordance with the heat output desired and a predetermined difference of 95
90 pressure between the supply and return pipes sufficient to move the steam through the radiating system, and a check valve in the return pipe which opens toward the generator. 100

11. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe connected with the generator, branch pipes leading from the outlets of the radiators to the return pipe, steam traps in said last named branch pipes, exhausting means connected with the return pipe so as to remove therefrom only non-condensable gases for maintaining a predetermined difference of pressure between the supply and return pipes sufficient to move the steam through the radiating system, and means cooperating with said exhausting means for controlling the amount of steam admitted into the radiating system so as to vary the temperature of 115
120 the steam in the radiators in accordance with the heat output desired. 125

12. In steam heating apparatus the combination of a steam generator, a radiating system comprising a plurality of radiators, a supply pipe leading from the generator and a drip pipe leading from the supply pipe back to the generator, branch pipes connecting the supply pipe with the inlets of said radiators respectively, a return pipe con- 130

5 nected with the generator, branch pipes leading from the outlets of the radiators to the return pipe, steam traps in said last named branch pipes, and heat control means comprising an exhausting means connected with the return pipe so as to remove therefrom only non-condensable gases said heat control means maintaining selected pressures below atmosphere in said radiators and a 10 predetermined difference of pressure between the supply and return pipes sufficient to move the steam through the radiating system, said exhausting means comprising a hurling water circuit and pump and means for eliminating non-condensable gases from the hurling circuit.

12. In steam heating apparatus the combination of a steam generator, a radiating system comprising a plurality of radiators, 20 a supply pipe leading from the generator and a drip pipe leading from the supply pipe back to said generator, branch pipes connecting the supply pipe with the inlets of said radiators respectively, a return pipe connected with the generator and extending above the water level therein to provide a hydrostatic head for return of water against the pressure in the generator, branch pipes leading from the outlets of the radiators to the return pipe, steam traps in said last named branch pipes, heat control means comprising an exhausting mechanism connected with the return pipe so as to remove therefrom only non-condensable gases, said heat control means maintaining a pressure below atmosphere in said radiators and a predetermined difference of pressure between the supply and return pipes sufficient to move the steam through said radiating system, 40 said exhausting mechanism comprising a hurling water circuit arranged below the water level of and connected with the generator to receive its hurling water therefrom and to discharge excess water thereto, a pipe between the supply and drip pipe and the return pipe, a steam trap in said last named pipe, a check valve in the return pipe which opens toward the generator and a float controlled air trap and eliminator connected with the return pipe and comprising an outwardly opening check valve.

13. In steam heating apparatus the combination of a steam generator, a radiating system comprising a plurality of radiators, 55 supply and return pipes connecting the radiating system with the generator for supply of steam to the radiating system and return of condensation to the generator, steam traps between the radiators and return pipes, 60 exhausting means which withdraws only non-condensable gases from the return piping for maintaining a predetermined difference of pressure between the supply and return pipes sufficient to move the steam through the radiating system, and means cooperating with

the exhausting means for controlling the amount of steam supplied to the radiating system to vary the temperature of the steam in the radiators in accordance with the heat output desired. 70

14. In steam heating apparatus the combination of a steam generator, a radiating system comprising a plurality of radiators, supply and return pipes connecting the radiating system with the generator for supply of steam to the radiating system and return of condensation to the generator, steam traps between the radiators and return pipes, through which both water and non-condensable gases pass to the return pipes, and heat control means including an exhausting mechanism which withdraws only non-condensable gases from the return pipes, said heat control means maintaining selected pressures below atmosphere in the radiators and a predetermined difference of pressure between the supply and return pipes sufficient to move the steam through the radiating system, said heat control means also including restricting devices at the inlets of the radiators for limiting the inflow thereto of steam to the maximum radiating capacity of said radiators respectively. 80

15. In steam heating apparatus the combination of a steam generator, a radiating system comprising a plurality of radiators, supply and return pipes connecting the radiating system with the generator for supply of steam to the radiating system and return of condensation to the generator, steam traps between the radiators and return pipes through which both water and non-condensable gases pass to the return pipes, heat control means comprising exhausting mechanism for withdrawing only non-condensable gases from the return pipes to maintain selected pressures below atmosphere in the radiators and a predetermined difference of pressure between the supply and return pipes sufficient to move the steam through the radiating system, and orifice plates in the inlets of the radiators for restricting the inflow of steam to the radiators. 100 105 110
